UNITED STATES PATENT OFFICE

121,027

DESIGN FOR A CABINET FOR SPACE HEATERS OR THE LIKE

George W. Walker, Detroit, Mich., assignor to
Lonergan Manufacturing Company, Albion,
Mich., a corporation of Michigan

Application July 13, 1939, Serial No. 85,985

Term of patent 3½ years

To all whom it may concern:

Be it known that I, George W. Walker, a citizen of the United States, residing at Detroit, in the County of Wayne and State of Michigan, have invented a new, original, and ornamental Design for a Cabinet for Space Heaters or the like, of which the following is a specification, reference being had to the accompanying drawings forming part thereof.

Fig. 1 is a perspective view of a cabinet for space heaters or the like embodying my new design; and

Fig. 2 is a fragmentary perspective view of the top portion of the cabinet shown in Fig. 1. The remaining portions are omitted for convenience of illustration.

The side of the cabinet not shown is substantially the same as the side shown.

I claim:

The ornamental design for a cabinet for space heaters or the like, substantially as shown and described.

GEORGE W. WALKER.
